US00D549697S

(12) **United States Design Patent** (10) **Patent No.:** **US D549,697 S**
(45) **Date of Patent:** **** Aug. 28, 2007**

(54) **DATA RELAY FOR WIRELESS
COMMUNICATION EQUIPMENT**

(75) Inventors: **So-Yoon Jeon**, Guri-si (KR); **Bum-Ho Chun**, Seoul (KR); **Sung-Il Bang**, Seoul (KR)

(73) Assignee: **Samsung Electronics Co., Ltd.** (KR)

(**) Term: **14 Years**

(21) Appl. No.: **29/260,200**

(22) Filed: **May 22, 2006**

(30) **Foreign Application Priority Data**

Mar. 9, 2006 (KR) 30-2006-0008575

(51) **LOC (8) Cl.** **14-03**

(52) **U.S. Cl.** **D14/240**

(57) **CLAIM**

We claim, the ornamental design for a data relay for wireless communication equipment, as shown and described.

DESCRIPTION

FIG. 1 is a perspective view of a data relay for wireless communication equipment, showing our new design;

FIG. 2 is a left side view thereof;

FIG. 3 is a right side view thereof;

FIG. 4 is a rear view thereof;

FIG. 5 is a front view thereof;

FIG. 6 is a top plan view thereof; and,

FIG. 7 is a bottom plan view thereof.
